UNITED STATES PATENT OFFICE.

MARTIN V. YORK, OF SHERMAN, TEXAS.

HAND SAWING-MACHINE.

SPECIFICATION forming part of Letters Patent No. 268,590, dated December 5, 1882.
Application filed September 6, 1882. (No model.)

To all whom it may concern:

Be it known that I, MARTIN V. YORK, a citizen of the United States, residing at Sherman, in the county of Grayson and State of Texas, have invented a new and useful Hand Sawing-Machine, of which the following is a specification.

My invention relates to improvements in hand sawing-machines in which a vertically movable frame-work supporting the driving mechanism operates in conjunction with a horizontally-reciprocating cross-head for carrying the saw; and the object of my improvements is to provide a portable hand-power machine for the rapid cutting of stove-wood, and for other light sawing. I attain these objects by the mechanism illustrated in the accompanying drawings, in which—

Figure 1 is a side elevation of the entire machine; Fig. 2, a back view of the same; and Fig. 3 a plan view through the line $x-x$, Fig. 1.

Similar letters refer to similar parts throughout the several views.

The platform A and standards B B, secured to its upper side, support the movable frame-work C of the machine. This frame-work is

balanced by weight D, and moves freely up or down between the standards. In the frame-work C turns the horizontal shaft E, furnished at both ends with handles F, by which it is driven.

G is a cog-wheel secured to it, gearing into a pinion, H, on the crank-shaft I. This shaft at one end carries a fly-wheel, J. From the crank I to cross-head α extends a connecting-rod, K, imparting to the cross-head and saw c , attached to it, the desired horizontal reciprocating movement. $e e$ are guides in which the cross-head slides.

The saw may be fed fast or slow by removing or adding to the weight D.

What I claim as new, and desire to secure by Letters Patent, is—

The combination, in a hand sawing-machine, of the standards B B and movable frame-work C, balanced as shown, with the gearing G and H, crank-shaft I, and reciprocating cross-head α , carrying saw c , all substantially as shown and set forth.

MARTIN V. YORK.
